UNITED STATES PATENT OFFICE.

HANS CHRISTIANSEN, OF BROOKLINE, MASSACHUSETTS, ASSIGNOR OF ONE-HALF TO
BERTHA K. JOHNSON, OF WAVERLEY, MASSACHUSETTS.

MOTOR-STARTING SWITCH.

1,402,342.

Specification of Letters Patent.

Patented Jan. 3, 1922.

Application filed September 23, 1919. Serial No. 325,655.

To all whom it may concern:

Be it known that I, HANS CHRISTIANSEN, a citizen of the United States, residing at Brookline, in the county of Norfolk and 5 State of Massachusetts, have invented new and useful Improvements in Motor-Starting Switches, of which the following is a specification.

This invention relates to switches employed to start relatively small alternating current motors of approximately seven and one-half horse power or less, and it has for its chief object to provide a switch having fuses which are of suitable capacity for use 10 with current of the ordinary voltage used when the motor is running normally, although inadequate for the increased or maximum current which is desirable in starting the motor, the switch having short-circuiting means adapted to protect the fuses against burning out under the overload resulting from the difference between the normal and the maximum current. In other words, the chief object of the invention is 15 to enable a motor-starting switch to be run with relatively light fuses without seriously endangering the fuses when a current of maximum voltage is temporarily employed in starting the motor. Another object of 20 the invention is to provide a switch having improved means whereby the circuit is automatically broken in the event of the burning out of a fuse.

The invention consists in the improvements which I will now proceed to describe and claim.

Of the accompanying drawings, forming a part of this specification:

Figure 1 is a front view of the switch, 40 with the casing covers removed, the solenoid being shown in section.

Figure 2 is an edge view, showing the casing in section and the enclosed parts in elevation.

Figure 3 is a view similar to a portion of Figure 1, parts shown by Figure 1 being removed.

Figure 4 is a section on line 4—4 of Figure 1.

Figures 5 and 5^a are fragmentary perspective views, showing one set of the secondary movable contact terminals or clips.

Figures 6, 7 and 8 are fragmentary front elevations, showing a portion of the fixed

base within the casing, and portions of the 55 switch mechanism associated therewith.

Figure 9 is a section on line 9—9 of Figure 6.

Figures 10 and 11 are edge views, showing the lower portions of the fixed base and 60 the fixed supporting bar hereinafter described, together with parts of the switch mechanism in different adjustments.

Figure 12 is a section on line 12—12 of Figure 6. 65

Figure 13 is a diagrammatic view, showing the members of one of the groups of contact terminals or clips.

The same reference characters indicate the same parts in all of the figures. 70

In the drawings:

20 represents a switch casing, of oblong form, and attached to a suitable support with its major axis in a vertical position, to permit downward movement, by gravity, 75 of the movable contact terminals or clips hereinafter described. A primary door 21, on hinges 22, closes the front of the casing, and has an opening closed by a secondary door 23, connected with the primary door 80 by hinges 24. The secondary door being recessed or offset, to receive the usual fuses 35 projecting through the primary door opening, as shown by Figure 2.

To the back of the casing 20 is fixed an 85 oblong, vertical base 26, of any suitable insulating material. To the base are fixed, by screws or bolts 27 (Figure 2), outwardly-projecting brackets 28 adapted to guide the carrier bars hereinafter described, and to 90 hold a fixed, vertical, supporting bar 29, of insulating material, which is fixed to the brackets by screws 30.

The switch mechanism includes a plurality of groups of contact terminals or clips, each 95 group being composed of the members shown diagrammatically by Figure 13, in which 31, 31 represent two fixed inner clips, attached to the base 26; 32, 32 represent two fixed outer clips, attached to the supporting 100 bar 29. The inner clips 31 are insulated from each other, and one of said clips is electrically connected with a generator 33 (Figure 13), the other with a motor 34. The outer clips 32 are electrically connected 105 with each other through a fuse 35 supported by spring clips or conducting arms 36 attached to the bar 29.

As best shown by Figure 10, the fixed clips 31 and 32 are oppositely inclined relatively to a vertical line midway between the clips, and are separated from each other 5 by a tapering space, the clips converging from their attached lower ends to their free upper ends. This arrangement of the fixed clips, and the corresponding arrangement of the primary and secondary movable clips, 10 are important for reasons which will appear.

38, 38 represent two inclined, movable, primary, inner clips, and 39, 39 two inclined, movable, primary, outer clips, said clips being connected by conducting strips 40. The said 15 movable primary clips are fixed to a vertically movable carrier, preferably composed of a pair of elongated vertical slides or bars 41, 41, and a cross bar 42 fixed to said slides, the clip-connecting strips 40 being 20 fixed to said cross bar. The slides or carrier bars 41 are spaced apart, and between them is located a single vertical slide or carrier bar 43, to which is fixed a cross bar 44.

45, 45 represent two inclined, movable, 25 secondary, inner clips, and 46, 46 represent two inclined, movable, secondary, outer clips, the clips 45 and 46 being electrically connected by conducting strips 47, and said conducting strips being connected by another 30 conducting strip 48. The secondary clips and conducting strips are fixed to the carrier cross bar 44. The carrier bars 41, 41 and 43 are guided in vertical paths by the brackets 28, and by guide rolls 49 journaled in 35 said brackets. The movable clips 38 and 39 are called the primary clips, and the movable clips 45 and 46 the secondary clips, only for convenience in distinguishing one set of 40 movable clips from the other. The primary and secondary clips are inclined like the 45 fixed clips 31 and 32, and they are movable by the respective carriers in vertical paths, the arrangement being such that the primary movable clips 38 and 39 may be raised into 50 contact with the fixed clips 31 and 32, and the secondary movable clips 45 and 46 may be raised into contact with the primary clips, all as shown by Figures 2 and 4. When the 55 clips are thus relatively positioned, the primary clips and the connecting strips 40 conduct current between the fixed clips 31 and 32 and the secondary clips, and the connecting strips 47 and 48 constitute a short-circuiting connection between the pairs of primary clips.

I have thus far confined the description to a single group of clips, and it will be understood that the switch shown by the drawings is suitable for a three phase motor, and has 60 three groups of clips, each accompanied by a fuse.

The object of the short-circuiting connections included in the groups of clips is to 65 protect the fuses during the starting of the motor, the clips being assembled as shown

by Figures 2 and 4 when the motor is being started, and the said short-circuiting connections carrying enough of the excess current to safeguard the fuses. After the motor has been started, the secondary clips are 70 lowered, as shown by Figure 11, the entire current then passing through the fuses.

For the convenient manual raising and lowering of the primary and secondary movable clips, I provide the means next described. 50 represents a hand lever, fulcrumed at 51 in the casing. The outer arm of the lever projects from the casing, and has a handle 52. The inner arm is connected by a link 53 with the lower end of the bar 80 43 of the secondary clip carrier. When the outer arm of the hand lever is depressed, the inner arm is raised and raises the bar 43, the carrier bars 41 and the primary and secondary movable clips to the position shown by 85 Figures 2 and 4, the full volume of current being thus supplied to start the motor.

The primary clips are locked in their raised circuit-closing position by means including a trip lever 55, which is pivoted at 90 56 to the fixed supporting bar 29, and has a longer outer arm projecting from the casing, and a hooked shorter arm 57. The trip lever 55 is connected with the hand lever 50 by a link 58, pivoted at 59 to the hand lever, 95 and having a slot 60, receiving a pin 61 on the trip lever 55. Fixed to a cross bar attached to the carrier bars 41, 41, is a stud 63. When the hand lever 50 is depressed, as shown by Figures 1 and 3, the lower end of 100 the slot 60 strikes the pin 61, and swings the trip lever 55 so that its hooked arm 57 engages the stud 63 and locks the carrier bars 41, 41 and the primary clips in their raised position. The secondary clips may now be 105 separated from the locked primary clips, as shown by Figure 11, by raising the outer arm of the hand lever 50, the slot 60 in the link 58 permitting this movement without moving the trip lever, so that the primary 110 clips remain in their raised position. It is obvious that the trip lever may be manually depressed to break the circuit. To cause the automatic displacement of the trip lever 55, and thus permit the descent by gravity of 115 the primary clips and their carrier to the position shown by Figure 10, in case a fuse burns out, I provide a solenoid, composed of a coil 65, having a vertical axis, and an armature 66, movable in a vertical path into 120 which the outer arm of the trip lever 55 projects, the coil of the solenoid being electrically connected, as shown by Figures 1 and 13, with two adjacent fixed clips 32, 32. When a fuse burns out, the armature 66 is 125 released, and falls by gravity with sufficient force to depress the outer arm of the trip lever, thus disengaging the hooked arm 57 from the stud 63, and permitting the primary clips and their carrier to drop, and 130

break the circuit. To prevent accidental downward movement of the armature 66, I provide a keeper 68, composed of an angular metal strip, loosely inserted in the upper end 5 of the coil, and contacting with the upper end of the armature when the latter is in its normal position, the ends of the keeper bearing loosely on a support at the upper end of the armature and retaining the latter in 10 place while the solenoid is energized.

To cushion the fall of the carrier bars, I provide a yielding buffer, as shown by Figures 6 and 10, composed of a cylinder 78, having a plunger 79, supported by a spring 15 80, and provided with an elastic rubber head 81. The cylinder is a part of a bracket attached at 82 to the base 26, the head 81 being in the path of one of the carrier bars 41 and arranged to yieldingly arrest the downward 20 movement of said bar.

The clips, inclined as shown, permit adequate contact when the movable clips are raised, without binding pressure on the movable clips, so that they are separable from 25 each other and from the fixed clips without having to overcome frictional resistance, so that the light force exerted by the solenoid armature in falling is sufficient to break the circuit.

I have hereinafter referred to the carrier for the primary clips as the primary carrier, and to the carrier for the secondary clips as the secondary carrier.

To permit free endwise movement of the carrier bars without binding on each other, I provide said bars with slots 85, receiving fixed studs 86 on the brackets 28, as shown by Figure 6.

I claim:

40 1. A motor-starting switch, comprising a plurality of groups of contact clips, each group including two pairs of spaced-apart fixed clips, a fuse connecting a member of each pair with a member of the other pair, 45 two pairs of primary movable clips adapted to serially connect the fixed clips, a short-circuiting connection including two pairs of secondary movable clips and adapted to serially connect the primary clips, and mechanism for moving said primary clips and short-circuiting connection to and from 50 their operative positions.

2. A motor-starting switch, comprising a plurality of groups of contact clips, each group including two pairs of spaced-apart fixed clips, a fuse connecting a member of each pair with a member of the other pair, two pairs of primary movable clips adapted to serially connect the fixed clips, a short-circuiting connection including two pairs of secondary movable clips and adapted to serially connect the primary clips, carriers for 55 said primary clips and short-circuiting connection, and manually operable means for moving said carriers.

3. A motor-starting switch, comprising a plurality of groups of contact clips, each group including two pairs of spaced-apart fixed clips, a fuse connecting a member of each pair with a member of the other pair, 70 two pairs of primary movable clips adapted to serially connect the fixed clips, a short-circuiting connection including two pairs of secondary movable clips and adapted to serially connect the primary clips, carriers 75 for said primary clips and short-circuiting connection, a hand lever adapted to raise both carriers, and a trip lever adapted to lock the primary carrier in its raised position, means being provided for engaging 80 said trip lever with the primary carrier by the carrier-raising movement of the hand lever, and for permitting depression of the secondary carrier while the primary carrier is raised. 85

4. A motor-starting switch, comprising a plurality of groups of contact clips, each group including two pairs of spaced-apart fixed clips, a fuse connecting a member of each pair with a member of the other pair, 90 two pairs of primary movable clips adapted to serially connect the fixed clips, a short-circuiting connection including two pairs of secondary movable clips and adapted to serially connect the primary clips, carriers for 95 said primary clips and short-circuiting connection, a hand lever adapted to raise both carriers, a trip lever adapted to lock the primary carrier in its raised position, and a link pivoted to the hand lever and having a 100 slot loosely receiving a stud on the trip lever, the arrangement being such that the link is adapted to move the trip lever to its operative position and to permit the depression of the secondary carrier while the primary carrier is raised. 105

5. A motor-starting switch, comprising a plurality of groups of contact clips, each group including two pairs of spaced-apart fixed clips, a fuse connecting a member of each pair with a member of the other pair, 110 two pairs of primary movable clips adapted to serially connect the fixed clips, a short-circuiting connection including two pairs of secondary movable clips and adapted to serially connect the primary clips, carriers for 115 said primary clips and short-circuiting connection, manually operable means for raising both carriers, a trip lever adapted to lock the primary carrier in its raised position, and a solenoid having a vertical axis and arranged with the path of its armature coincident with a portion of the trip lever, so that the dropping of said armature displaces the trip lever and permits the primary carrier and its clips to drop. 120

6. A motor-starting switch, comprising a plurality of groups of contact clips, each group including two pairs of spaced-apart fixed clips, a fuse connecting a member of 125

each pair with a member of the other pair, two pairs of primary movable clips adapted to serially connect the fixed clips, a short-circuiting connection including two pairs of 5 secondary movable clips and adapted to serially connect the primary clips, carriers for said primary clips and short-circuiting connection, manually operable means for raising both carriers, a trip lever adapted to 10 lock the primary carrier in its raised position, and a solenoid having a vertical axis and arranged with the path of its armature coincident with a portion of the trip lever, so that the dropping of said armature dis-

places the trip lever and permits the primary carrier and its clips to drop, a buffer being provided to cushion the drop of said carrier. 15

7. A switch substantially as specified by claim 1, said fixed inclined clips being separated by a tapering space, and said movable clips being correspondingly inclined and adapted to move in a vertical path into and out of said space. 20

In testimony whereof I have affixed my 25 signature.

HANS CHRISTIANSEN
